UNITED STATES PATENT OFFICE.

WILL H. McCARTY, OF ROLLING PRAIRIE, INDIANA.

INGROWING-TOE-NAIL PROTECTOR.

SPECIFICATION forming part of Letters Patent No. 440,434, dated November 11, 1890.

Application filed August 1, 1890. Serial No. 360,726. (No model.)

To all whom it may concern:

Be it known that I, WILL H. McCARTY, a citizen of the United States, residing at Rolling Prairie, in the county of La Porte and State of Indiana, have invented a new and useful Ingrowing-Toe-Nail Protector, of which the following is a specification.

This invention relates to surgery, and more particularly to devices for curing ingrowing toe-nails; and the object of the same is to effect improvements upon devices of this character heretofore constructed.

To this end the invention consists, broadly speaking, of a metallic strip secured to the body of the toe with one end passed beneath the ingrowing edge of the nail, all as herein-after more fully described, and as illustrated in the drawings, in which—

Figure 1 is a plan view of a foot, showing my improved protector as applied to the toe thereof. Fig. 2 is a bottom plan of the same. Fig. 3 is an enlarged front elevation of the protector detached.

It is common in this class of devices to provide an expandable spring having hooks at its ends taking over the edges of the nail, which spring exerts a gentle force to press the flesh back from the nail on each side; but it often occurs that the nail is "ingrowing" at but one edge and the insertion of the hook beneath the other edge and pressure upon the flesh at that side soon causes the flesh to recede undesirably from the nail there. Moreover, in any case, if one hook becomes disengaged and slips out of place, the entire device springs off the toe and its utility ceases. The present invention is designed to overcome these objections by providing a device acting on but one edge of the nail and held in position by gentle clamping action upon the body of the toe, whereby it cannot become displaced.

Referring to the said drawings, the letter F designates a human foot, upon one of the toes of which a nail N is illustrated as ingrowing 45 at the right edge.

The letter P designates my improved protector, which consists of a thin strip of spring metal coiled so that it is adapted to surround the toe and pinch gently upon the same with 50 its front end E bent beneath the ingrowing edge of the nail. If desired, the end of the spring, after the latter makes several coils around the toe, may be continued between two of the toes, as shown in dotted lines, in 55 order to prevent the whole protector from turning upon the toe.

It is to be understood that the protector may be made in various sizes, and either "right" or "left" to be applied to nails which may be 60 ingrowing at the corresponding edge. The front end E may be also made of varying widths and shapes, whereby toes of different shapes may be fitted, as will be readily understood.

Having thus described my invention, what I claim, and desire to secure by Letters Patent of the United States, is—

The herein-described device for curing ingrowing nails, the same consisting of a strip 70 of spring metal in the shape of a coil adapted to surround the toe, the front end of said strip being bent down and adapted to pass beneath the ingrowing edge of the nail, all as hereinbefore set forth.

In testimony that I claim the foregoing as my own I have hereto affixed my signature in presence of two witnesses.

WILL H. McCARTY.
